Primary Examiner — Anhdao Doan(74) *Attorney, Agent, or Firm* — Popovich, Wiles & O'Connell, P.A.(57) **CLAIM**

The ornamental design for a landscaping block, as shown and described.

DESCRIPTION

FIG. 1 is a front perspective view of a first embodiment of a landscaping block;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof;

FIG. 8 is a front perspective view of a second embodiment of a landscaping block;

FIG. 9 is a front elevational view thereof;

FIG. 10 is a rear elevational view thereof;

FIG. 11 is a top plan view thereof;

FIG. 12 is a bottom plan view thereof;

FIG. 13 is a left side elevational view thereof;

FIG. 14 is a right side elevational view thereof;

FIG. 15 is a front perspective view of a third embodiment of a landscaping block;

FIG. 16 is a front elevational view thereof;

FIG. 17 is a rear elevational view thereof;

FIG. 18 is a top plan view thereof;

FIG. 19 is a bottom plan view thereof;

FIG. 20 is a left side elevational view thereof;

FIG. 21 is a right side elevational view thereof;

FIG. 22 is a front perspective view of a fourth embodiment of a landscaping block;

FIG. 23 is a front elevational view thereof;

FIG. 24 is a rear elevational view thereof;

FIG. 25 is a top plan view thereof;

FIG. 26 is a bottom plan view thereof;

FIG. 27 is a left side elevational view thereof; and,

FIG. 28 is a right side elevational view thereof.

The broken lines in the drawing views are included for the purpose of illustrating portions of the landscaping block that form no part of the claimed design.
